UNITED STATES PATENT OFFICE.

SAMUEL SELDEN, OF ERIE, PENNSYLVANIA.

DOOR-HANGER.

SPECIFICATION forming part of Letters Patent No. 246,642, dated September 6, 1881.

Application filed March 21, 1881. (Model.)

To all whom it may concern:

Be it known that I, SAMUEL SELDEN, a resident of Erie, in the county of Erie and State of Pennsylvania, and a citizen of the United States, have invented new and useful Improvements in Door-Hangers; and I do hereby declare that the following is a full, clear, and exact description thereof, reference being had to the accompanying drawings and the letters or figures of reference marked thereon.

My invention relates to the construction and attachment of the sheaves or wheels of hanging sliding doors.

My device is shown in the accompanying drawings, as follows:

Figure 1 is a perspective view, showing the side of a building, a part of a sliding door, my hanger, and the track on which the sheave runs, *h* being the flange of the part *H* and entirely distinct from the sheave *W*. Fig. 2 is a vertical section through the hanger, door, track, and side of building.

The parts shown are indicated by letters of reference, as follows:

A is the door, and *A'* a strip on the outside of the door, which latter, however, is not essential in many forms of doors. *B* is the side or wall of the building; *C*, a strip, either upon the building or door, for closing the space between the door and the building. *T* is the track on which the sheaves run; *W*, the wheel or sheave; *H*, a stud on which is formed the journal or axis of the wheel, and *h* a flange on said stud; *E*, a flanged washer; *D* and *D'*, a bolt and nut, and *d* a washer enlarging the head of the bolt.

The primary object of my invention is to produce a strong, durable, and cheap hanger, and it may be applied to various kinds of overhanging doors, such as barn-doors, car-doors, gates, &c.

All the door-hangers of this class with which I am acquainted (except some for inside work, like hanging sliding doors for parlors, &c., which are hung directly above the door and run on a double track) have the bracket-iron attached to the outside of the door, and a shank or neck crosses over the top of the door, so as to bring the sheave directly above the door upon a track overhanging the door. Such a construction, however, is faulty, in that the shank or neck of the bracket-iron often breaks

off between the journal of the sheave and the place where the iron is attached to the door; also, the attachment of said bracket-iron, being generally made by common wood-screws, is apt to work loose.

It is the purpose of my invention to overcome these objections.

In my device the door is carried up past the side of the track, and the sheave is placed on the inside of the door. This brings the door away from the wall somewhat; but I fill the space with the cleat *C*, and thus overcome that difficulty. The advantages derived from such a construction will appear hereinafter.

My hanging device is constructed as follows: *H* is a round stud, which enters a hole bored through the door near the top. This stud has a large flange, *h*, which gives a facing upon the side of the door. It also has a part forming the axis or journal of the sheave *W*. It is also perforated throughout its length to receive the bolt *D*. A washer, *d*, or, if desired, an enlargement of the head of the bolt, serves to hold the sheave upon its journal. A flanged washer, *E*, on the outside of the door sets in the stud-hole in the door, and serves as a bearing for the nut *D'* on the bolt *D*, and also as a facing on that side of the door. An ordinary plain washer, however, may be used at this point, and perhaps serve every purpose. When the nut *D'* is tightened the door is clamped between the washer *E* and the flange *h* on the stud *H*, and the wheel or sheave is properly held in place upon the journal provided on the stud.

This construction is very simple, strong, and cheap, and it is quickly and easily attached to the door. The one bolt *D* holds all the parts in place. No wood-screws are used, and consequently the fastening is solid and durable. If desired, the following modifications may be made in the construction:

The stud *H* may pass clear through the door, and, in place of the bolt, a screw-thread and nut at each end of the stud may be used—one to serve in the place of the washer *d* and the other in place of the nut *D'*. The stud *H* need not pass into the door at all, but be attached thereto by bolts passing through the flange and the door. In this case, if the bolt *D* is omitted, as it may be, there must be provided a proper device for holding the sheave upon its axis in

place of the washer *d*. That part of the stud *H* which passes through the door may be omitted, and the bolt only pass through the door. Such variations, however, do not depart 5 from the line of my invention, and, while they might serve as well, they do not, I believe, present as perfect a device as that shown.

What I claim as new is—

1. A sliding door having a hanging device 10 consisting of a sheave, by which the door is suspended, and a flanged stud, forming the axis of said sheave, attached to said door on the side thereof next the wall of the building by being socketed in a hole in the door below the top of 15 the same, and secured by a nut at its outer end, substantially as shown.

2. In a door-hanger, the combination, substantially as described, of the following elements: a sheave, *W*, the hollow stud *H*, with flange *h*, a journal for the sheave, and means, 20 substantially as shown, for attaching the same to the door.

In testimony that I claim the foregoing I have hereunto set my hand this 15th day of March, 1881.

SAMUEL SELDEN.
